UNITED STATES PATENT OFFICE.

EDWARD H. WRAY, OF PHILADELPHIA, AND LOUIS M. PYLE, OF BRYN MAWR, PENNSYLVANIA, ASSIGNORS TO NILES-BEMENT-POND COMPANY, OF JERSEY CITY, NEW JERSEY, A CORPORATION OF NEW JERSEY.

HAMMER-PRESS.

1,044,617.

Specification of Letters Patent. Patented Nov. 19, 1912.

Application filed July 18, 1912. Serial No. 710,109.

To all whom it may concern:

Be it known that we, EDWARD H. WRAY and LOUIS M. PYLE, citizens of the United States, residing at Philadelphia, Philadelphia county, Pennsylvania, and Bryn Mawr, Montgomery county, Pennsylvania, respectively, have invented certain new and useful Improvements in Hammer-Presses, of which the following is a specification.

10 This invention pertains to improvements in hammer presses, being forging machines designed to accomplish the forging by impactive hammer blows and by squeezing pressure. A given piece of work being done 15 in a hammer press may, in some cases, be done by the hammer action alone, while in other cases it may be done by the press action alone, while in still other cases it may be done by the press action following the 20 hammer action or vice-versa.

Our invention will be readily understood from the following description taken in connection with the accompanying drawing in which:—

25 Figure 1 is a vertical diametrical section of the hammer and press cylinders: Fig. 2 a horizontal section of the same in the plane of line *a* of Fig. 1: and Fig. 3 an enlarged reproduction of the lower lefthand portion 30 of the cylinder-work seen in Fig. 1.

In the drawing:—1, indicates a portion of the frame, such as is employed in an ordinary steam hammer: 2, a hydraulic cylinder supported by the frame with its axis vertical, this cylinder being closed at its top and open at its base: 3, a steam cylinder disposed concentrically within the hydraulic cylinder: 4, a head secured above the hydraulic cylinder: 5, a hollow cylindrical boss whose interior forms the steam cylinder 3: 6, a steam passage leading to the upper end of steam cylinder 3: 7, a steam passage leading to the lower end of steam cylinder 3: 8, a steam-chest, of not unusual construction, having a 40 steam inlet and an exhaust outlet and having ports communicating with the steam passages 6 and 7 and containing an ordinary valve for controlling the flow of steam to and from the upper and lower ends of steam cylinder 3: 9, the steam piston, disposed within the steam cylinder 3: 10, the piston-rod: 11, the ram, connected with the steam

piston rod as usual in steam hammers: 12, an annular hydraulic-plunger disposed within hydraulic cylinder 2 around steam cylinder 3, this plunger projecting downwardly from the hydraulic cylinder: 13, a foot-piece secured to the base of the hydraulic plunger and adapted to rest upon ram 11: 14, cup-leather packing rings disposed in the hydraulic cylinder around the lower portion of hydraulic plunger 12: 15, rings secured to the base of the cylinder structure, one within and the other exterior to the hydraulic plunger, these rings having lips projecting inwardly under the packing rings: 16, the hammer-die secured to the ram 11 in the manner usual in steam hammers: 17, a movable support adapted to be moved to position under foot-piece 13 when the latter is in upper position: 18, a passage leading to the upper end of the hydraulic cylinder and adapted for communication with a source of supply of water under pressure and under valved control, as is usual in hydraulic presses: and 19, rings disposed over the lips of rings 15 and under the cup-leather packing-rings.

Assuming the parts to be in the position indicated in Fig. 1, but further assuming that support 17 is swung under foot-piece 13 and that water-passage 18 is open to exhaust, the hydraulic plunger is supported in its upper position and the steam hammer parts represented by the ram and hammer-die and piston and valve may be used in the ordinary manner of steam hammers precisely as though the hydraulic plunger were absent. If, now, support 17 be displaced from under the hydraulic piston water under pressure be admitted through passage 18 the hydraulic plunger 12 will be forced down, forcing the ram and hammer-die down and causing the hammer-die to exercise its pressing action upon the work. If, when the hydraulic plunger moves downward, there be steam under the steam piston then that steam will simply be forced back to the source of steam supply. When the parts are in lower position and passage 18 is open to exhaust, if steam be admitted below the steam piston it will elevate the parts and the hydraulic plunger may, if desired, be again locked in upper position by the

support 17. It is desirable that the hydraulic plunger be locked in elevated position whenever it is out of use and the apparatus is being used strictly as a steam hammer.

5. Those skilled in the art relating to hammer presses will be familiar with numerous modifications in the manner of working hammer presses and the fact will be appreciated that our present invention well lends itself to these modifications. For instance, in the supplying of pressure liquid to the hydraulic press of a hammer press it is customary to produce the stroke of the hydraulic plunger, or to fill the hydraulic cylinder as the plunger descends, with water at low pressure, and to produce the final squeezing action by admitting water at high pressure, as from an accumulator or intensifier over the hydraulic plunger. And in the present invention this can be accomplished by means of the usual hydraulic press connections communicating with passage 18. Again, steam hammers are in some cases operated by means of steam employed alternately below and above the steam piston, and, in other cases, by means of steam acting only below the steam piston and serving to lift the hammer which descends by 30 gravity when the steam below the piston is released.

Our present invention manifestly lends itself to either system of steam hammer operation, though we have seen fit to illustrate 35 the apparatus as arranged for the use of steam above as well as below the piston. Most any of the valve arrangements and valve gears usually employed in connection with steam hammers and hydraulic presses 40 and hammer presses can be availed of in connection with our present invention. It is also to be understood that steam hammers, so called, are sometimes operated by compressed air. The steam hammer portion 45 of our present invention manifestly lends itself to operation by air, and it is to be understood that the term steam, as employed in this specification, comprehends any other suitable elastic fluid as its equivalent.

50. We claim:

1. A hammer-press comprising, a steam cylinder, a piston therein, a piston-rod connected with the piston, a ram and hammer-die connected with the piston-rod, an annular hydraulic cylinder concentrically surrounding the steam cylinder, an annular hydraulic plunger disposed within the hydraulic cylinder and projecting therefrom 60 toward the ram, and a connection between the hydraulic plunger and the ram, combined substantially as set forth.

2. A hammer-press comprising, a steam cylinder, a piston therein, a piston-rod connected with the piston, a ram and hammer-

65 die connected with the piston-rod, an annular hydraulic cylinder concentrically surrounding the steam cylinder, an annular hydraulic plunger disposed within the hydraulic cylinder and projecting therefrom 70 toward the ram, and a connection rigid with the hydraulic plunger and adapted for downward contact with but unattached to the ram, combined substantially as set forth.

3. A hammer-press comprising, a steam cylinder, a piston therein, a piston-rod connected with the piston, a ram and hammer-die connected with the piston-rod, an annular hydraulic cylinder concentrically surrounding the steam cylinder, an annular hydraulic plunger disposed within the hydraulic cylinder and projecting therefrom 75 toward the ram, a connection between the hydraulic plunger and the ram, and a movable support to maintain the hydraulic plunger in upward position independent of the ram, combined substantially as set forth.

4. A hammer-press comprising, a steam cylinder, a piston therein, a piston-rod connected with the piston, a ram and hammer-die connected with the piston-rod, an annular hydraulic cylinder concentrically surrounding the steam cylinder, an annular hydraulic plunger disposed within the hydraulic cylinder and projecting therefrom 80 toward the ram, and a foot-piece secured to the hydraulic plunger and surrounding the piston-rod and adapted to engage over the ram, combined substantially as set forth.

5. A hammer-press comprising, a hydraulic cylinder, a boss containing a steam-cylinder and disposed concentrically within the hydraulic cylinder, a piston in the steam cylinder, a piston-rod and ram and hammer-die connected with the piston, an annular hydraulic plunger disposed within the hydraulic cylinder and around the steam cylinder, a connection between the hydraulic plunger and the ram, cup-leather rings inside and outside the annular hydraulic plunger, and separable supports disposed below 105 said cup-leather rings, combined substantially as set forth.

6. A hammer-press comprising, a hydraulic cylinder, a boss containing a steam-cylinder and disposed concentrically within the hydraulic cylinder, a piston in the steam cylinder, a piston-rod and ram and hammer-die connected with the piston, an annular 110 hydraulic plunger disposed within the hydraulic cylinder and around the steam cylinder, a connection between the hydraulic plunger and the ram, cup-leather rings disposed in annular recesses in the bases of the 115 hydraulic cylinder and boss and inside and outside the hydraulic plunger, rings disposed within said recesses and forming abutments for the cup-leather rings, and rings separably secured to the bases of the 120

hydraulic cylinder and boss and forming abutting supports for the first mentioned rings, combined substantially as set forth.

7. A hammer-press comprising, a hydraulic cylinder open at its lower end, an annular hydraulic plunger disposed within said hydraulic cylinder and projecting downwardly therefrom, a head secured to the upper end of the hydraulic cylinder, a boss projecting downwardly from said head within said annular hydraulic plunger, and containing a steam cylinder concentric with

the hydraulic cylinder, a steam chest carried by said head, a piston in the steam cylinder, a piston-rod projecting downwardly from the piston, a ram and hammer-die connected with the piston-rod, and a connection between the bases of the hydraulic plunger and the ram, combined substantially as set forth.
